UNITED STATES PATENT OFFICE.

CHARLES P. EISENHAUER, OF DAYTON, OHIO, ASSIGNOR TO THE DURO COMPANY, OF DAYTON, OHIO, A CORPORATION OF OHIO.

WATER-SOFTENING APPARATUS.

Application filed July 26, 1926. Serial No. 124,932.

My invention relates to water softening apparatus and in particular to equipment used with automatic water softening apparatus.

5 My invention is particularly adaptable to that type of water softening apparatus, which is more fully set forth and described in my co-pending application Serial No. 41,580.

10 The particular invention involved in this application relates to the operation of the brine valve and the refill valve and the control thereof.

It is my object to provide an interlocking 15 float control mechanism by which the refill valve and brine valve may be both locked in a predetermined position.

Referring to the drawings:

Figure 1 is a section through the unitary 20 combination of a refill valve and brine valve with associated passageways and mechanism;

Figure 2 is a plan view thereof;

Figure 3 is a section on the line 3-3 of 25 Figure 1;

Figure 4 is a section on the line 4-4 of Figure 3.

Referring to the drawings in detail, 1 is a brine line, through which either passes 30 brine or water to refill the brine tank. In this line is connected at 2 a pipe 3, which communicates the pressure on the side of the softener to the diaphragm chamber 4. This diaphragm chamber has its top formed by 35 the housing 5 and bottom formed by the yielding diaphragm 6.

This diaphragm engages with a plate 7 carried on the upper end of a valve stem 8 of the brine valve. This valve stem also 40 carries a locking plate 9 which is engaged by a spring 10 resting on the shoulder 11 which serves to maintain the valve in closed position. The locking plate 9 is also engaged by the locking head of the plunger 12, the operation of which will be more fully 45 described hereinafter.

Returning to the brine valve stem 8, it will be observed that it passes through a packing 13 held in position by a packing 50 gland 14 and a spring 15 within the cage

16. To this valve stem passes through the pipe 17 forming a continuation of the brine line and into the interior thereof.

A partition 18 is arranged transversely in this line separating it from the pipe 19 which leads into the brine tank. A valve seat 20 is provided in the partition about the aperture 21 therein, the lower side of which valve seat is adapted to be engaged by the valve 22 carried on the valve stem 8 to close the opening 21.

Returning to the other side of the mechanism, it will be observed that a valve member 23 known as the refill valve is provided for closing an opening 24 in a partition 25 which separates the passageway in the pipes 17 from the passageway in the pipe 1. This valve member 23 is carried on a refill valve stem 26.

The valve stem passes upwardly through 70 a packing 27, a gland 28 within a packing spring 29 in a cage 30. 31 is a valve spring controlling the valve stem 26 by engaging with a locking plate 32 which is carried on the valve stem. On the upper end of the 75 valve stem is a plate 33 engaging with a yielding diaphragm 34 forming the bottom of a refill valve diaphragm chamber 35. Communicating with this chamber is a pipe 36 which leads from the master control valve 80 not shown, which is a part of the water softening apparatus.

The refill valve is adapted to be locked in position by the plunger 37 engaging with the locking plate 32.

The plunger 37 is engaged by an arm 38 pivoted at 39 and having connected thereto a float arm 40, the free end of which carries the usual float in the brine tank. This arm 38 is also connected to the plunger 12 in the 90 following manner.

A sleeve 41 is carried on the plunger 38 within which sleeve moves the plunger 12. The plunger 12 is guided therein by the shoulders 42 thereon working in the slots 43 of the sleeve 41. The outside of this sleeve is threaded at 44 and carries a thimble 45 through the free end of which the plunger 12 is adapted to freely operate. Between the outside end of this thimble and an abutment 100

46 carried on the plunger 12 is a spring
47. This arrangement permits of the varia-
tion of the overall dimension in length of the
two locking plungers, the necessity for
5 which will be seen from the following de-
scription of the operation of this machine.

Operation.

When the apparatus ceases its softening
10 operation and is converted into regenerating
position, it will be found that the pressure
which has existed in the line 1 of water has
been communicated through the pipe 3 to
the diaphragm chamber 4 and has been
15 maintaining the brine valve 22 open. The
locking plunger 12 has, as a result, moved
into locking position and locked this valve
open.

Thus, when the regeneration starts, which
20 consists of drawing brine water through the
pipe 19, pipe 17 and pipe 1 into the system,
due to the action of the injector in the sys-
tem, the brine valve will be open to allow
the passage of liquid. At the same time, the
25 liquid pressure which is behind the dia-
phragm 6 will be decreased due to the in-
jecting action and the suction on the water
in the neighborhood of the opening 2 of the
pipe 3.

30 Pressure will be set up in the line 36 in
the diaphragm chamber 35 due to admission
of such pressure through the needle control
valve of the system. This results in de-
pressing the diaphragm 34 and locking plate
35 32. This results in the plunger 37 moving
into locking position as the float and float
arm descend. It is obvious that it is not de-
sired to withdraw the plunger 12 so that the
yielding connection between the two plun-
30 gers, as shown in Figure 3, is desirable per-
mitting both plungers to remain in locking
position, while their overall length increases
between their respective ends.

45 The continued descent of the float and
float arm eventually, when sufficient brine
has been extracted from the tank, cause the
arm 38 to withdraw the plunger 12, which
permits of the shutting of the valve 22.

50 The depression of the diaphragm 34 has
opened the refill valve 23 permitting the con-
tinuous flow of brine from the brine tank.

55 While the brine is shut off, water is run-
ning through the system to flush out the
brine and when this ceases the softener is
drawn over to softening position with the re-
sult that the pressure is decreased in the
line 36 and increased or set up in the cham-
ber 4 through the line 3 so that the valve
22 is held open by this pressure, and the
60 valve 23 can close if it is unlocked by the
lock 37. This results in both valves 22 and
23 being open permitting the water to flow
into the brine tank.

65 This causes the float to rise in the tank
with the result that the lock 37 is pulled out

at the appropriate time and the refill valve
23 is closed, thus shutting off a further sup-
ply of water from the brine tank.

It will be understood that, when this re-
filling operation starts, the valve 23 is held 70
open by hydrostatic pressure and the valve
23 is locked open.

It will be understood that I desire to com-
prehend within my invention such modifica-
tions as may be necessary to adapt it to vary- 75
ing conditions and uses.

Having thus fully described my invention,
what I claim as new and desire to secure by
Letters Patent, is:—

1. In a water softener, a refill valve, a 80
brine valve, means to deliver hydrostatic
pressure to open the refill valve, means to
deliver hydrostatic pressure to open the brine
valve, locking means for said respective
valves, a common float actuating means for 85
said locking means actuated by the level of
brine in a brine tank, and a brine line adapt-
ed to convey brine in one direction and refill
water in the other direction controlled by
said refill and brine valves. 90

2. In a water softener, a refill valve, a brine
valve, means to deliver hydrostatic pressure
to open the refill valve, means to deliver
hydrostatic pressure to open the brine valve,
locking means for said respective valves, a 95
common float actuating means for said lock-
ing means actuated by the level of brine in
a brine tank, and a brine line adapted to con-
vey brine in one direction and refill water in
the other direction controlled by said refill
and brine valves, and means to yieldingly
100 vary the distance between the ends of said
locking means.

3. In a water softener, a brine valve and a
refill valve, a pipeway for conveying brine
water and refill water controlled by said
valves having a brine supply at one end and
a softening apparatus at the other end, a
line for conveying hydrostatic pressure to
110 operate the brine valve extending from the
pipe line on the side of the softener to be-
hind the brine valve, a second hydrostatic
line adapted to be connected to the incoming
water of the softener and to the refill valve
115 for actuating the refill valve, interconnected
locking means for said respective valves to
lock them open and a common float means
adapted to alternately actuate said locking
means, and yielding means for returning
120 said valves to their closed position.

4. In a water softener, a pipe line adapted
to convey brine water and refill water con-
nected on its respective sides to a brine tank
and a softening apparatus, transverse parti-
tions in said pipe line having apertures
therethrough and valve seats therein, a refill
valve and a brine valve adapted to close said
passageways, yielding means for closing said
valves, locking means for locking said valves
open, diaphragms connected to said respec- 130

tive valves for receiving hydrostatic pressure to open said valves, means for conveying hydrostatic pressure to a point behind the brine valve from a point between the softening apparatus and the refill valve in the pipe line, means to convey hydrostatic pressure from the incoming hard water of the softener to behind the refill valve and float means supported in a brine supply for alternately actuating said locking means.

5. In combination, spaced refill and brine valves controlling a pipe, a pipe, hydrostatic and yielding means for actuating said

valves, one of said hydrostatic means deriving its pressure from the pipe and the other from pressure exteriorly of the pipe, interconnected locking means for locking said valve members open, a common float member for alternately locking and unlocking said locking means, and means for varying yieldingly the overall length between the ends of said locking means.

In testimony whereof, I affix my signature.

CHARLES P. EISENHAUER.
